UNITED STATES PATENT OFFICE.

NATHAN M. LOWER, OF PITTSBURGH, PENNSYLVANIA. ASSIGNOR TO LOCOMOTIVE STOKER COMPANY, A CORPORATION OF PENNSYLVANIA.

RESILIENT TROUGH SUPPORT.

Application filed June 14, 1924. Serial No. 720,141.

To all whom it may concern:

Be it known that I, NATHAN M. LOWER, a citizen of the United States, and resident of Pittsburgh, county of Allegheny, and State of Pennsylvania, have invented certain new and useful Improvements in Resilient Trough Supports, of which the following is a specification, and which is illustrated in the accompanying drawings, forming a part thereof.

This invention relates to stokers, and more particularly to stokers for locomotives.

The principal object of the invention is the provision of new and improved means for supporting a great portion of the weight of the stoker independently of the locomotive.

Another object of the invention is the provision of new and improved means for supporting the entire weight of the conveyor and a portion of the weight of the elevator from the tender.

Other and further objects and advantages will appear from the following description taken in connection with the accompanying drawings, in which

Fig. 1 is a vertical section of a portion of a locomotive and tender therefor, showing the invention in position thereon; and Fig. 2 is a vertical section of the resilient support.

In the construction of railway rolling stock in recent years the tendency has been to build larger and still larger locomotives. But the bridges, tracks and road beds on most roads determine the maximum weight of the locomotives that may be employed. Owing to the great size of the locomotives of the present time, the employment of mechanical stokers to supply fuel thereto is absolutely necessary. In present practice, a great portion of the weight of these stokers is carried by the trucks of the locomotive, thereby adding to the weight of the same. Where the weight of the engines as designed is only slightly below the maximum for safety on the roads on which they are intended to operate, the extra weight of the stoker on the locomotive might add sufficient weight to exceed that amount.

In order to relieve the locomotive trucks of a great portion of this added weight, and

support the same from the tender, suitable mechanism has been provided which will now be described.

On the drawing, the reference character 10 designates a locomotive and 11 the tender therefor. The coupling mechanism for connecting the locomotive and tender together is conventionally shown at 13.

Suitable means are provided for transferring the fuel from the tender to the locomotive. This means comprises a conveyor 14 and an elevator 15. The rear portion 65 of the conveyor 14 is in the form of a trough 16 which is located beneath the floor 17 of the tender 11 whereby fuel from said tender may fall by gravity into said trough and be transferred by the conveyor element 18 to the elevator 15 and by means 70 of the elevator mechanism 19 delivered to the distributor 20, in the usual manner.

The forward end of the conveyor 14 is connected to the elevator 15 by a universal joint 21 as is common in such constructions. The conveyor 14 is supported on the tender frame 22 by appropriate mechanism provided for this purpose. That shown comprises the bearings 23 secured to said conveyor which are adapted to engage tracks 24 rigidly secured to said frame. The bearings may if desired be so located that the weight of the conveyor, the conveyor screw, the coal in said conveyor and the mechanism at the rear for operating the screw will be borne principally by the bearings 23.

Suitable means are provided preventing undue oscillation of the conveyor and for supporting the forward end of the same 90 from the tender. As shown on the drawing, a resilient support is employed for this purpose. The resilient support comprises a lower section 25 which is rigidly secured to the frame 22 of the tender as by means of the bolts or screws 26. The section 25 is provided with an upwardly extending tubular member 260 which is adapted to receive the lower end of the supporting spring 27. A cap member 28 which telescopes the upper end of the member 260 is adapted to receive the upper end of the spring 27 whereby a housing is provided for said spring.

The upper end of the cap 28 is adapted to 105 engage a bearing surface 29 formed on the

lower portion of the conveyor 16 for permitting longitudinal and lateral movement of said conveyor.

- The spring 27 is of such size that it will 5
5 not only support the entire weight of the front end of the conveyor 14 but will also assist in supporting the weight of the elevator 15 on the locomotive. The resiliency of the spring will permit a limited vertical 10
10 movement of the conveyor 14 in order that the same may conform to the movement of the elevator 15 during the travel of the locomotive and may be so constructed and arranged that it will also support a part of 15
15 the weight of the elevator.

By means of this arrangement not only the entire weight of the conveyor 14 is supported on the tender, but also a portion of the weight of the stoker may be carried by 20
20 the tender, thus enabling stokers to be employed on locomotives that approach the maximum weight permitted on the roads on which they are to be employed.

This invention is not limited in its application to the particular construction herein illustrated, as various changes might be made in the construction shown without departing from the spirit of this invention, or the scope of the appended claims.

30 I claim as my invention:

1. In combination, a locomotive, a tender therefor, a stoker for supplying fuel to said locomotive from said tender, comprising a conveyor and an elevator, and means including a resilient member for supporting the entire weight of said conveyor on said tender.

2. In combination, a locomotive, a tender therefor, a stoker for supplying fuel to said locomotive from said tender, comprising a conveyor and an elevator, means for supporting the rear end of said conveyor on said tender, and resilient means for supporting the forward end of said conveyor on said tender.

45 3. In combination, a locomotive, a tender, a stoker for said locomotive comprising a fuel conveyor and an elevator, a track on said tender, a supporting member secured

to said conveyor for engaging said track for 50 supporting one end of said conveyor, and resilient means for supporting the other end of said conveyor.

4. In combination, a locomotive, a tender, stoker mechanism for said locomotive including a conveyor, and means, said means exerting a lifting force on the front end only of said conveyor, for supporting said conveyor from said tender, said means slidably engaging said conveyor to permit 60 lateral horizontal oscillation of one end of said conveyor relatively to said tender and said means.

5. In combination, a locomotive, a tender, stoker mechanism for said locomotive including a conveyor located beneath the deck of the tender and an elevator, a universal joint between said conveyor and elevator, the latter being mounted on said locomotive, and means for supporting said conveyor and 70 a portion of the weight of said elevator from said tender, said means exerting a lifting force through said joint on said elevator.

6. In combination, a locomotive, a tender 75 therefor, conveyor means located on the tender, elevating means mounted on the locomotive and interlocking with the conveyor means, and resilient means located on the tender for urging such two means upwardly.

7. In combination, a locomotive, a tender therefor, stoker mechanism located in part on the tender and in part on the locomotive, and resilient means on the tender for supporting in part both of such sections of the stoker mechanism.

8. In combination, a locomotive, a tender therefor, stoker mechanism comprising an elevator mounted on said locomotive for supplying fuel thereto, a conveyor for transferring fuel from said tender to said elevator, and means on said tender for supporting said conveyor, said means exerting a lifting force on said elevator for relieving the engine of a portion of the weight of said elevator.

NATHAN M. LOWER.
